UNITED STATES PATENT OFFICE.

HENRY DICKINSON, OF FLUSHING, NEW YORK.

SWITCH-OPERATING MECHANISM.

No. 796,196.

Specification of Letters Patent.

Patented Aug. 1, 1905.

Application filed December 19, 1904. Serial No. 237,400.

To all whom it may concern:

Be it known that I, HENRY DICKINSON, a citizen of the United States, residing at Flushing, in the county of Queens and State of New York, have invented a new and useful Switch-Operating Mechanism, of which the following is a specification.

The object of this invention is to provide a new and improved switch-operating mechanism, particularly adapted for use on electric railways, whereby the motorman can throw the switch from his platform to direct the car the way desired.

The particular object of this invention is to provide a simple durable apparatus of this nature which can be cheaply put in place and which will work and lock the switch in a simple and effective manner.

Referring to the two sheets of drawings, forming part of this application, Figure 1 is a perspective view of a rail and switch with my improved device applied thereto. Fig. 2 is a plan view of the switch, illustrating the operating connections, this figure being turned oppositely relatively to Fig. 1 and the remaining figures on Sheet 1 matching with Fig. 2. Fig. 3 is a plan view, Fig. 4 a sectional view, and Fig. 5 an end elevation, of the switch-throwing mechanism. Fig. 6 is a plan view, and Fig. 7 a side elevation, of the mechanism mounted on the car; and Fig. 8 is a detail view of the mechanism shown in Fig. 6.

The device can be best understood by referring to the figures.

In detail, A designates a rail, coacting with which is a usual pivoted point-switch S. An arm 10 is pivoted at 11 to the web of the rail A, the said pivot 11 coming at about the center of the web, so that the arm 10 extends both sides of the web. A prolongation 12 of said arm 10 connects to the switch S. This prolongation is made out of spring metal, so that the switch will be held with a spring-pressure to the rail, whereby if a car comes in the reverse direction along the main rail when the switch is close thereto the switch will yield slightly, so that the wheels can pass the same. Carried by the rail which carries the switch, a suitable distance in advance of the same, is a switch-operating mechanism. This mechanism is constructed as follows: Bolted to each side of the rail is a bracket 13, secured to the top of which is a guide-plate 14, which has a way 15. Running on each guide-plate 14 is a shoe 16, which has antifriction-rollers 17, which run on said way. The shoes 16 at each

side of the rail are rights and lefts. Connected to the shoes are bell-crank levers 18, which are pivoted to brackets 19, bolted to the sides of the rails. The right-hand bell-crank lever 18, relatively to Fig. 3, is connected by a rod 20 to the operating-arm 10, and the left-hand bell-crank is connected by a similar rod 21 to the operating-arm 10. The rods 20 and 21 extend along and lie on opposite sides of the web of the rail. Pivoted in each shoe 16 on the opposite side of the guide-plate 14 relatively to the antifriction-rollers 17 is a bell-crank lever 22. The horizontal ends of said bell-crank levers are pivoted together, as at 23, and extending down therefrom is a latch 24, which is adapted to engage the web of the rail at either side thereof, the web being cut away, as shown in Fig. 4, for this purpose. The other ends of the bell-crank levers 22 come in position shown in Fig. 4 to operate, as hereinafter described.

It will be seen that the mechanism hereinbefore described is all connected and carried by the rail, whereby boxes or compartments are dispensed with.

Referring now to the mechanism on the car, it will be seen that brackets 25 25 are secured to the under side of the platform, and journaled in the same is a shaft 26. Fitted on said shaft 26 are sleeves 27 27, which are connected to turn together by a connection 28. (See Fig. 8.) The shaft and sleeves are also supported by a center bracket 29, in which one of the sleeves is journaled. Secured to the shaft 26 are weighted arms 30 30, which carry at their outer ends cam-operating pieces 31 31, which may be moved down to operative position to engage the outside of the rail A. These cam-pieces are secured to the weighted arms by strips of spring metal 32, which strips extend up and are guided in suitable brackets extending down from the platform, as shown in Fig. 7. By this arrangement the cam-operating pieces 31 31 are yieldingly held when they are brought to operative position.

To operate the shaft 26, an arm 33 is secured thereon, which connects by a suitable link to a lever 34, pivoted on the center bracket 29. A foot-treadle 35 extends down through the platform and connects to said lever 34. By this construction when the foot-treadle 35 is depressed the cam-operating pieces 31 31 are brought down to engage the outside of the rails, and when the foot-treadle is released the said cam-operating

pieces will normally swing up clear of the rails. Arranged on the sleeves 27 27 are similar weighted arms 36, which carry cam-operating pieces 37 37, which are adapted to fit to the inside of the rails, these cam-operating pieces being connected to the weighted arms by pieces of spring metal similar to the pieces 32, previously described. Arranged on one of the sleeves is an arm 38, which connects by a suitable link to a lever 39, which connects with a treadle 40, arranged beside the treadle 35. By depressing the treadle 40 the cam-operating pieces 37 37, which come inside of the rail, will be brought to operative position. The cam-operating pieces 31 31 and 37 37 have ribs 41, as shown in Fig. 1, to engage with the bell-crank levers 22 to operate the locking mechanism for the shoes.

The device works as follows: In Fig. 2 the switch S is shown as set to the rail or to operative position, the shoes then standing, as shown in Fig. 3—that is, the right-hand shoe being closer to the rail than the left-hand shoe. Suppose now that a car comes along up toward the switch. If the motorman wishes to let the car go over onto the switch, the parts are in proper position for this purpose; but suppose that he wishes to go straight ahead on the rail A. In this event before the car-wheels reach the shoe he depresses the treadle 40. This will throw the cam-operating pieces 37 37, which engage the inside of the rails into operative position. The cam-operating piece 37 which lies on the rail which the switch engages will now run along and wedge in between the rail and the right-hand operating-shoe, as shown in Fig. 3. As this action takes place the rib 41 will engage the bell-crank lever 22 in the right-hand shoe, which will lift the latch 24, so that the shoes will be moved to the right, as shown in Fig. 4, which will pull on the rod 20 and push on the rod 21, whereby the switch S will be thrown away from the rail A. It will be seen that the rods 20 and 21 are arranged to move parallel to the rail, whereby the operating-shoes can be arranged at any desired distance in advance of the switch, and special designing is not required for each location. As the shoe moves to the right the latch 24 will move over the web of the rail and will lock the switch in its new or inoperative position. If the switch should be found set in inoperative position to let the car be run along the rail A and if it should be desired to bring the switch into operation, the operator presses the treadle 35, which brings the cam-pieces 31 31 into operation, which work on the outside of the rails, whereby the left-hand shoe will be engaged, the rod 21 pulled, and the rod 20 pushed and the switch thrown into operative position. The two sets of cam-operating pieces 31 31 and 37 37 are used so that the motorman can control a switch, no matter with which rail it is arranged. For example,

if a switch is arranged in connection with the other rail from that referred to in Figs. 2 and 3, as shown in Fig. 1, the same operation will take place, the other cam-piece 31 coming into operation if it is desired to go along the main track or to the right or the other cam-piece 37 coming into operation if it is desired to use the switch and go to the left. In other words, all that the motorman has to remember as he approaches the switch is to touch the treadle 35 if he wishes to go to the right or the treadle 40 if he desires to go to the left, no matter with which rail the switch is arranged. The motorman has to exert very little power, as the wedging of the particular cam-operating piece which comes into operation between the rail and the shoe does the work. It will also be seen that the parts are automatically unlocked and locked as they operate. It also will be seen that the device can be very easily put in position, as all the parts are carried by and secured to the rails.

The details herein shown and described may be greatly varied by a skilled mechanic without departing from the scope of my invention as expressed in the claims.

Having thus fully described my invention, what is claimed, and desired to be secured by Letters Patent, is—

1. In a switch-operating mechanism the combination of the switch, a shoe carried by the rail, connections arranged to move parallel to the rail from said shoe to the switch, and a cam-operating piece carried by the car for wedging between the rail and shoe to operate the switch.

2. In a switch-operating mechanism, the combination of the switch, shoes carried by the rail at opposite sides thereof, connections arranged to move parallel to the rail from said shoes to the switch, and two cam-operating pieces carried by the car for wedging between the rail and the shoe to operate the switch.

3. In a switch-operating mechanism, the combination of the switch, a shoe carried by the rail, connections therefrom to the switch, a locking mechanism for the shoe, and an operating-piece carried by the car for unlocking the shoe and for wedging in between the same and the rail to operate the switch.

4. In a switch-operating mechanism, the combination of the switch, shoes carried by the rail at opposite sides thereof, connections therefrom to the switch, four operating-pieces and two treadles carried by the car, one treadle being arranged to throw two operating-pieces into position inside of the rails, and the other treadle being arranged to throw two operating-pieces into position outside of the rails.

5. In a switch-operating mechanism, the combination of the switch, a shoe carried by the rail, connections arranged to move parallel to the rail from the shoe to the switch, and

a cam-operating piece yieldingly carried by the car for wedging between the rail and the shoe to operate the switch.

6. In a switch-operating mechanism, the combination of the switch, shoes carried by the rail, connections therefrom to the switch, a shaft and sleeve carried by the car, operating-pieces carried by the shaft and sleeve, a foot-treadle connected to the shaft, and a foot-treadle connected to the sleeve.

7. In a switch-operating mechanism, the combination of the switch, shoes carried by the rail, connections therefrom to the switch, a bell-crank lever carried by each shoe, a latch carried by the bell-crank levers, and operating-pieces carried by the car.

8. In a switch-operating mechanism, the combination of the switch, brackets extending

from the rail, shoes mounted thereon and running on antifriction-rollers, connections from the shoes to the switch, and operating-pieces carried by the car.

9. In a switch-operating mechanism, the combination of the switch, a shoe carried by the rail, connections therefrom to the switch, locking mechanism for the shoe, and an operating-piece carried by the car and having a rib to operate the locking mechanism and move the shoe to actuate the switch.

In testimony whereof I have hereunto set my hand in the presence of two subscribing witnesses.

HENRY DICKINSON.
